METAL WINDOW

Filed Nov. 9, 1936

UNITED STATES PATENT OFFICE

2,112,634

METAL WINDOW

Charles D. Pilant, Alhambra, Calif.

Application November 9, 1936, Serial No. 109,894

2 Claims. (Cl. 189—69)

My invention relates to a metal window and has for its principal object the provision of a window wherein a plurality of metal sash, each carrying a glass panel, are mounted for simultaneous swinging movement in a metal frame, and such sash and frame having associated therewith means constructed of metal for imparting swinging movement to the sash, thus providing a construction that is entirely fire-proof.

10 Further objects of my invention are to provide a metal window having a plurality of glazed sash that are burglar-proof by reason of the fact that the small size of the individual sash prevents an intruder from crawling through the opening in 15 the sash, even though the panel of glass is entirely removed therefrom; further, to construct the window frame and the sash so as to effectively prevent rain from being blown by the window through the joints between the edges of the metal 20 sash and the window frame.

Further objects of my invention are to provide improved means for imparting swinging movement to the sash; further, to provide simple and efficient means for securing the sash operating 25 means so that the sash cannot be opened or closed from the exterior of the window; and, further, to provide a construction that will prevent the ingress of dust while the sash are closed.

With the foregoing and other objects in view 30 my invention consists in certain novel features of construction and arrangements of parts that will be hereinafter more fully described and claimed and illustrated in the accompanying drawing, in which:

35 Fig. 1 is an elevational view of a metal window with parts broken away.

Fig. 2 is a vertical section taken on the line 2—2 of Fig. 1.

Fig. 3 is an enlarged horizontal section taken 40 on the line 3—3 of Fig. 1.

Fig. 4 is an enlarged horizontal section taken on the line 4—4 of Fig. 1.

Fig. 5 is an enlarged horizontal section taken on the line 5—5 of Fig. 2.

45 Fig. 6 is an enlarged horizontal section taken on the line 6—6 of Fig. 1.

Fig. 7 is an elevational view of a rack and pinion construction that may be used for imparting swinging movement to the sash.

50 Fig. 8 is a side elevational view of the form of sash swinging mechanism seen in Fig. 7.

Referring by numerals to the accompanying drawing which illustrates a preferred embodiment of my invention, 10 designates the upper 55 member of the window frame, which member is

substantially L-shaped in cross section, and the horizontal flange 11 of said member lies against the building wall at the top of the window opening and the vertical flange 12 lies against the outer face of the building wall just above the 5 window opening.

Vertically disposed side members of the window frame include outer flanges 13 that occupy the same plane with the flanges 12 of top member 10, and said flanges 13 overlie the outer face 10 of the building wall to the sides of the window opening. These upright members also include vertically disposed plates or flanges 14 that lie against the faces of the building wall to the 15 sides of the window opening to the rain, and said 15 plates or flanges are connected to the flanges 13 by inclined plates 15.

The bottom member of the frame comprises an outer flange 16 that occupies the same plane with the flanges 12 and 13, and this flange 16 20 lies against the outer face of the building wall below the window opening therein. The lower member also includes a horizontally disposed plate or flange 17 that rests on top of the building wall at the bottom of the window opening 25 therein and connecting the plates or flanges 16 and 17 is an inclined plate or flange 18. Formed integral with or fixed to the underside of plate or flange 11 is a plate 19, and formed integral with and depending therefrom are spaced parallel flanges 20 and 21.

Extending downwardly and outwardly from the front edge of plate 19 is an inclined plate or flange 22. Formed integral with or fixed to the inner faces of the upright side members of 35 the frame are inwardly presented parallel flanges 23 and 24 which occupy the same planes respectively with the flanges 20 and 21.

Formed integral with and projecting upwardly from plate or flange 17 are spaced parallel 40 flanges 25 and 26 that occupy the same planes respectively with the flanges 20 and 23 and 21 and 24.

Where the window is provided with four swinging sash the flanges 21 and 26 are connected by a vertically disposed bar 27 that occupies a point midway between the upright side members of the frame and connecting the intermediate portion of this vertically disposed bar with the flanges 24 on the upright side members 50 are horizontally disposed bars 28.

Formed integral with or fixed to the upper edges of the horizontal bars 28 are outwardly and 55 downwardly projecting flanges 29 that are parallel with the inclined flanges 18 and 22. Formed

integral with and secured to the outer face of the vertical bar are inclined plates or flanges 38 against which the vertically disposed side members of the swinging sash are adapted to engage when the sash are closed.

5 Connected by suitable hinges 31 to the lower edge of the inclined flange or plate 22 are the inclined upper rails 32 of the sash frames and the upper faces of which rails are inclined so as to fit snugly against the under faces of the flanges 22 when the sash are closed.

10 The upright side members or rails 33 of the sash frames are inclined so as to fit snugly against the inclined portions 15 of the upright side members of the window frame and against the inclined flanges 38 on rail 27 when the sash are closed.

15 The under faces of the lower rails 34 of the sash frames are inclined so as to fit snugly against the inclined plate 29 and the inclined portion 18 of the lower window frame member when the sash are closed.

20 All of the sash frames are preferably formed of metal rails, the ends of which are welded to each other to provide integral structures.

25 It will be understood that the upper rails 32 of the upper sash in the window frame bear against the inclined flange 22 at the top of the window structure and that the upper rails of the lower sash are hinged to the lower edge of the inclined flange 29 and bear against the underside of said inclined flange when the sash are closed (sec Fig. 2).

30 Arranged for vertical sliding movement on the inner face of the vertical bar 27 is a bar 35 in the upper and lower portions of which are formed slots 36, and passing through said slots and seated in the bar 27 are hinged pins or screws that retain the sliding bar against said bar 27.

35 Secured to the central part of the exposed face of the sliding bar 35 is a knob 38 that is utilized in raising and lowering said sliding bar.

40 Pivotedly connected to the intermediate portions of the vertically disposed side members 33 of the hinged sash are the lower ends of links 39, the upper ends thereof being secured to the sides of the sliding bar 35. As a result of this arrangement the sash will be swung outwardly into positions shown in dotted lines in Fig. 2, when 45 the sliding bar 35 is moved downwardly, and when said bar is moved upwardly the sash will be simultaneously closed.

45 Knob 38 is provided with a threaded shank 46 in order that, after the sliding bar has been moved vertically in either direction, it may be secured in its shifted position by tightening the knob so as to cause the inner end of the threaded shank to engage with clamping pressure against the central portion of bar 27.

50 Removably positioned in the inner portion of the window frame and bearing against the flanges 20, 23 and 25 is a metal frame carrying a metal screen 41, the same being retained in position within the frame by hooks 42 that are 55 rotatably mounted in the upper and lower rails of the screen frame.

55 In Figs. 7 and 8, I have illustrated a simple and convenient means for swinging the sash upon their hinges and which means includes a vertically disposed rack bar 43 that is secured 60 on the face of the lower portion of the sliding bar 35 adjacent one edge thereof.

65 Mounted on bar 27 adjacent the projecting portion of rack bar 43 is a plate 44 having bearings 45 in which is journaled a shaft 46 and secured

on the latter is a worm wheel 47 and a pinion 48 that engages the teeth of rack bar 43.

70 Projecting forwardly from the lower portion of plate 44 is a bracket 49 in which are journaled the trunnions of a worm 50 that engages the worm wheel 47, and formed in the end of the exposed trunnion of this worm is a non-circular recess 51 that is adapted to receive the non-circular end of a key or crank shaft 52 that is utilized for rotating the worm.

75 Where this sash operating mechanism is used the rotation of worm 50 by the crank or key 52 imparts rotary movement to worm 47 and the pinion 48 and the latter engaging the teeth of rack 43 imparts longitudinal sliding movement to bar 35.

80 Thus it will be seen that I have provided an all-metal and glass window that is relatively simple in construction, inexpensive of manufacture, and very effective in performing the functions 20 for which it is intended.

85 The size of the sash frames is such as to prevent burglars or intruders from entering the window after the glass in the sash has been broken, thus providing a burglar-proof construction.

90 Inasmuch as the outer edges of the rails or sash frames are inclined or bevelled and engage against correspondingly inclined or beveled faces on the window frame when the sash are closed, ingress of dust and rain blown by the wind through the window when the sash are closed is effectively prevented.

95 By providing suitable means for locking the sash to the window frame in closed position, my improved window may be advantageously used in jails, detention homes or other buildings where persons are confined.

100 It will be understood that minor changes in the size, form and construction of the various parts of my improved metal window may be made and substituted for those herein shown and described without departing from the spirit of the invention, the scope of which is set forth in the appended claims.

105 I claim as my invention:

1. In a metal window, a substantially rectangular frame adapted to be positioned in a window opening, said frame comprising a pair of upright side members, a top member, a bottom member, and an intermediate horizontally disposed member, the vertically disposed side members being provided with outwardly bevelled faces, the outer portions of the top, bottom and intermediate members being provided with inclined faces, flanges projecting inwardly from said side members, top member and bottom member, a vertically disposed bar connecting the intermediate portions of the flanges on the top and bottom member, said bar provided on its outer portion with a pair of oppositely arranged inclined faces, glazed metal sash hinged to the top and intermediate members of the frame below the inclined faces thereon, the upright side members of the sash having bevelled faces that are adapted to engage the bevelled faces on the upright side members of the frame, the top and bottom rails of the sash having bevelled faces that engage the inclined faces on the top, bottom and intermediate rail and bar of the window frame when the sash are closed.

110 2. In a metal window, a substantially rectangular frame adapted to be positioned in a window opening, said frame comprising a pair of upright side members, a top member, a bottom member,

and an intermediate horizontally disposed member, the vertically disposed side members being provided on their outer portion with outwardly bevelled faces, the top, bottom and intermediate members being provided with correspondingly inclined faces, a pair of spaced parallel flanges depending from the underside of the top member of said frame, pairs of spaced flanges projecting inwardly from the side members of said frame, a pair of spaced flanges projecting upwardly from the bottom member of said frame, the respective members of which flanges occupy the same vertical planes, a vertically disposed bar connecting the intermediate portions of the outer one of the flanges on the top member and the outer one of

the flanges on the bottom member, the outer portion of said vertically disposed bar having a pair of oppositely arranged inclined surfaces, glazed metal sash hinged to the top and intermediate members of the frame below the inclined faces thereon, the upright side members of the sash having bevelled faces that are adapted to engage the bevelled faces on the upright side members of the frame and the oppositely inclined faces on said vertically disposed bar, and the top and bottom rails of the sash having bevelled faces that engage the inclined faces on the top, bottom and intermediate rails of the window frame when the sash are closed.

CHARLES D. PILANT. 15
